CLAIM

The ornamental design for a clip-on power strip, as shown and described.

DESCRIPTION

FIG. 1 is a front top perspective view of a clip-on power strip showing my new design;

FIG. 2 is top view of the clip-on power strip;

FIG. 3 is bottom view of the clip-on power strip;

FIG. 4 is a right side view of the clip-on power strip;

FIG. 5 is a left side view of the clip-on power strip;

FIG. 6 is a rear view of the clip-on power strip; and,

FIG. 7 is a front view of the clip-on power strip.

The broken lines in the drawings are for the purpose of illustrating portions of the clip-on power strip that form no part of the claimed design.
